CLAIM

The ornamental design for speaker housing, as shown and described.

DESCRIPTION

FIG. 1 is perspective view of a speaker housing showing our new design;

FIG. 2 is a second perspective view thereof;

FIG. 3 is a bottom plan view thereof;

FIG. 4 is a top plan view thereof;

FIG. 5 is a front elevation view thereof;

FIG. 6 is a rear elevation view thereof;

FIG. 7 is a left-side elevation view thereof; and,

FIG. 8 is a right-side elevation view thereof.

The portions shown in broken lines form no part of the claimed design.
